COOKING RANGE

George C. Clarke, Newark, Ohio, assignor to Sears, Roebuck and Co., Chicago, Ill., a corporation of New York

Filed Sept. 8, 1959, Ser. No. 57,477

Term of patent 3½ years

(Cl. D81—4)

Fig. 1 is a front perspective view of a cooking range with the surface heating unit in retracted position; and

Fig. 2 is a similar view of the same showing said unit in forwardly extended position.

The side of the range not shown is a mirror image of the side shown, and the top is plain.

The dominant features of the design reside in the portions shown in full lines.

I claim:

The ornamental design for a cooking range, as shown and described.
